UNITED STATES PATENT OFFICE.

ALBERT H. SAWTELL, OF WINTHROP, MASSACHUSETTS.

WARP STOP-MOTION FOR LOOMS.

1,170,681.

Specification of Letters Patent.

Patented Feb. 8, 1916.

Application filed March 29, 1915. Serial No. 17,631.

To all whom it may concern:

Be it known that I, ALBERT H. SAWTELL, a citizen of the United States, and a resident of Winthrop, in the county of Suffolk and State of Massachusetts, have invented an Improvement in Warp Stop-Motions for Looms, of which the following description, in connection with the accompanying drawings, is a specification, like characters on the drawings representing like parts.

This invention relates to warp stop motions which may be of general application but which are more particularly adapted for use in connection with broad looms.

In order that the principle of the invention may be readily understood, I have disclosed a single embodiment thereof in the accompanying drawing, wherein—

Figure 1 is a vertical, sectional view of a broad loom having my invention applied thereto; Fig. 2 is a detail showing one of the loom cross braces; Fig. 3 is a plan view upon a large scale illustrating the preferred arrangement of drops; and Fig. 4 is a view partially in side elevation and partially in vertical section illustrating the preferred arrangement of drops.

So far as I am aware, drop wires have not been successfully used upon broad looms and particularly because of the fact that the cross brace or cross braces thereof are so positioned as to interfere with the indicating movement of the drops.

An important object of my invention is to provide a warp stop motion peculiarly adapted for use in broad looms for weaving silk or worsted goods, though within the scope of the invention the drop mechanism may be used in other relations and in other types of looms than broad looms.

My warp stop mechanism is peculiarly adapted for use in conjunction with electrical means for stopping looms, but within the broad scope and purpose thereof, it may be used in connection with mechanical means for such purpose.

Referring more particularly to the drawing, I have therein indicated one side frame of the loom at 1, it being of any suitable construction. The warp 2 is let off from the usual warp beam not herein shown and passes over a whip roll 3, the woven cloth being accumulated upon the take-up roll, not shown, in any suitable manner. I have indicated at 4 a shed formed in the warp. Preferably and in this embodiment of the

invention between said shed and the whip roll 3, I position the drops which are therefore herein shown as supported upon the warp ends at a point where they are not affected by the shedding movement. The loom is provided with one or more cross-braces 5 secured in any suitable manner to the frame of the loom, and preferably to a center piece 6, as by bolts indicated at 7. 60 One of these cross braces is indicated in detail in Fig. 2.

At opposite sides of the loom, I provide two brackets 8 adapted to be secured at the proper height by means of bolts 9 passing through slots or elongated openings 10. Preferably each bracket 8 is thus adjustably secured to a lower bracket 11 itself secured to the adjacent member of the loom frame by bolts 12. Preferably adjacent the upper 70 edge of the bracket 8 I provide guides 13 extending from side to side of the loom and from which the warp ends pass and whereon they are supported as indicated in Figs. 1, 3 and 4. Said warp ends are thus supported in non-leashed condition upon said brackets 8, and therefore extend in a horizontal path as indicated in said figures. I provide for a suitable number of banks of 75 drop devices. In the disclosed form of my 80 invention, I have represented four such banks. More or fewer may be employed.

Referring particularly to the preferred and selected embodiment of my invention, I have herein represented four guide bars 14, 90 15, 16, 17 whereon are supported in suitable projections 18, 19, 20, 21 extending from the brackets 8, sets of drops 22, 23, 24, 25, each of which preferably though not necessarily has an open ended slot 26 which may be enlarged at the upper end as indicated at 27 for the reception of the proper warp end 2.

Preferably but not necessarily the warp stop motion herein disclosed is of the electrical type in which case the guide bars 14, 100 15, 16 and 17 constitute one terminal. I have herein represented each drop as provided with lateral shoulders 28, 29, with which coöperate stop rods or other devices 30 located over said shoulders, so as to prevent the drops from being unduly lifted because of the movement of the warp ends.

Each drop is preferably provided with two shoulders, so that the drops may be reversed in position if desired. If as preferred the warp stop be an electrical one, the 105 guide bars 14, 15, 16, 17, constituting one

terminal, are suitably connected to conductors 31 leading to an electro-magnet 32 which is energized upon completion of the circuit.

5 My experiments have demonstrated that drop wires, being of exceedingly thin sheet metal, are very apt to twist when they drop into indicating position, and in such manner as to interfere with their most effective operation. After much experimentation, I have ascertained that this defect may be fully overcome by so shaping or constructing the lower end portions of the said drops as to embrace or partially surround in their 10 fallen or indicating position the co-acting stop member which, in the case of an electrical warp stop mechanism constitutes the other terminal of such mechanism.

15 I have herein represented four bars or 20 tubular members 33, 34, 35, 36, from which lead conductors 37 also extending to the electromagnet 32, so that upon the movement of a drop into indicating position, the loom is stopped in a manner not herein 25 necessary more fully to describe.

30 Preferably, though not necessarily, the terminal bars 33, 34, 35, 36 are made curved in cross section, and they are herein represented as circular. Whatever be their cross 35 sectional shape, I correspondingly shape the lower ends of the drops 22, 23, 24, 25, which are shown as recessed or concaved at 38.

35 The construction and relation of the parts is such that the concaved lower end 38 of 40 a fallen drop fits snugly upon the bar 33, 34, 35, 36 therebeneath, and in such manner that by reason of said engagement and the supporting bar 14, 15, 16, 17, the drop is held firmly and without twisting.

45 The length of the drops is such that even in their indicating position, they are above and out of contact with the members or cross braces 5, as is most clearly evident from the position of the indicating drop in Fig. 1.

50 In Fig. 3, I have indicated four warp ends *a, b, c, d*, whereon are respectively supported the drop devices 22, 23, 24, 25, the arrangement of said devices depending upon the number of banks thereof. While the drop 55 devices indicated may be of different sizes, within the scope of my invention, I have, in Fig. 4, represented them as of the full or actual size preferred in practice. From the construction and arrangement of parts 60 therein represented, it will be evident that an indicating drop will fall but a very short distance before the recessed lower end 38 comes in contact with the terminal bar 33, 34, 35, 36, and that in its indicating position, 65 it will be out of contact with the cross brace 5. Thus, my warp stop mechanism peculiarly coöperates with a loom provided with a cross brace.

Because of the preferred non-leased arrangement of the warp ends, the drop de-

vices are supported at a higher position than would be the case with leased warps, the construction and arrangement whereof are disclosed in the patent to Coldwell and Gildard, Reissue No. 11,923, dated July 31, 1901.

Having thus described one illustrative embodiment of my invention, I desire it to be understood that although specific terms are employed, they are used in a generic and descriptive sense and not for purposes of limitation, the scope of the invention being set forth in the following claims.

Claims:

1. A warp stop motion for looms comprising in combination, means to support a set 80 of warp ends, a set of forked drop devices supported thereon, a stop member whereon said set of drop devices is mounted, and a co-acting stop member consisting of a rod substantially circular in cross section and 85 mounted below said drop devices, and spaced and distinct from said stop member, the lower ends of the drop devices being concaved to fit upon said co-acting stop rod when in indicating position.

2. A warp stop motion for looms comprising in combination, means to support a set of warp ends, a set of forked drop devices supported thereon, each drop device having a lateral shoulder or shoulders, stop devices 95 above said lateral shoulders but below the warp ends, a stop member whereon said drop devices are mounted, and a co-acting stop member mounted below said drop devices and spaced and distinct from said stop member, the lower ends of the drop devices being recessed to fit upon said co-acting stop member when in indicating position.

3. In a broad loom having a cross brace 105 connected to the loom frame beneath and in proximity to stop devices, means to support a set of warp ends in non-leased condition, sets of short drop devices supported on said non-leased portions of said warp ends with 110 their upper ends in substantially the same plane, a series of stop members whereon said drop devices are mounted in sets, and a series of co-acting stop members mounted below said drop devices but above said 115 cross brace, and spaced and distinct from said series of stop members, the lower ends of said drop devices being shaped to fit upon said respective co-acting stop members when in indicating position, said parts being so 120 relatively located that a drop in indicating position and in contact with the co-acting stop member is out of contact with said cross brace.

4. In a broad loom having a cross brace 125 connected to the loom frame beneath and in proximity to stop devices, means to support a set of warp ends in non-leased condition, sets of short drop devices supported on said non-leased portions of said warp 130

ends with their upper ends in substantially the same plane, a series of stop members whereon said drop devices are mounted in sets, and a series of co-acting stop rods 5 mounted below said drop devices but above said cross brace, and spaced and distinct from said series of stop members, the lower ends of said drop devices being recessed to embrace said rods when in indicating position, said parts being so relatively located 0 that a drop in indicating position and in contact with the respective rod is out of contact with said cross brace.

5. In a broad loom having a cross brace connected to the loom frame beneath and in proximity to stop devices, means to support a set of warp ends in non-leased condition, sets of short drop devices supported on said non-leased portions of said warp 0 ends with their upper ends in substantially the same plane, a series of electrical contact rods upon which said drop devices are supported, and a co-acting series of electrical 5 contact rods mounted below said drop devices but above said cross brace, the lower ends of said drop devices being shaped to embrace said lower rods when in indicating position, said parts being so relatively located 0 that a drop in indicating position and in contact with its said rod is out of contact with said cross brace.

6. A warp stop motion for looms comprising in combination, a cross brace 5 connected to the loom frame beneath and in proximity to stop devices, means to support a set of warp ends, a set of drop devices 22 slotted at 26 and supported upon said warp ends, a stop member 14 whereon said set of short drop devices is mounted and a co-acting stop member 33 mounted below said drop devices spaced and distinct from said

stop member, but above the said cross brace 5 of the loom, the lower ends of the said drop devices being recessed at 38 to fit upon said coacting stop member 33 when in indicating position. 45

7. In a broad loom having a cross brace connected to the loom frame beneath and in proximity to stop devices, means to support a set of warp ends in non-leased condition, sets of short drop devices supported on said non-leased portions of said warp ends and stopping means with which an indicating drop contacts, said stopping means being positioned above said cross 50 brace and in such position relative thereto that a drop in indicating position and in contact with said stop means is out of contact with said cross brace. 55

8. In a broad loom having a cross brace connected to the loom frame beneath and in proximity to stop devices, means to support a set of warp ends in non-leased condition, sets of short drop devices supported on said non-leased portions of said warp ends, a series of stop members whereon said drop devices are mounted in sets, and a series of co-acting stop members mounted below said drop devices but above said cross 60 brace and spaced and distinct from said 65 series of stop members, said parts being so relatively located that a drop in indicating position and in contact with the co-acting stop member is out of contact with said cross brace. 70 75

In testimony whereof, I have signed my name to this specification, in the presence of two subscribing witnesses.

ALBERT H. SAWTELL.
